DESIGN FOR A BROOCH OR THE LIKE

Marcel Boucher, New York, N. Y.

Application January 6, 1940, Serial No. 89,830

Term of patent 3½ years

To all whom it may concern:

Be it known that I, Marcel Boucher, a citizen of the United States and a resident of the Borough and county of Richmond, city and State of New York, have invented a new, original, and ornamental Design for a Brooch or the like, of which the following is a specification, reference being had to the accompanying drawing, forming part thereof.

Fig. 1 is a front view and Fig. 2 is a side view of a brooch showing my new design.

The figures are shaded to show contrasting colors.

I claim:

The ornamental design for a brooch or the like, as shown and described.

MARCEL BOUCHER.
